(57) **CLAIM**

The ornamental design for a spine of a binder, as shown and
described.

DESCRIPTION

FIG. 1 is an isometric view of a spine of a binder.

FIG. 2 is an inside top plan view of the spine of a binder of
FIG. 1.

FIG. 3 is an outside top plan view of the spine of a binder
of FIG. 1.

FIG. 4 is an end view of the spine of a binder of FIG. 1.

FIG. 5 is the opposing end view of the spine of a binder of
FIG. 4.

FIG. 6 is a side view of the spine of a binder of FIG. 1.

FIG. 7 is the opposing side view of the spine of a binder of
FIG. 6.

FIG. 8 is an enlarged partial end view of the spine of a binder
of FIG. 4.

FIG. 9 is an enlarged isometric view of the spine of a binder
of FIG. 1 taken along circle 9 of FIG. 1.

FIG. 10 is an enlarged inside top plan view of the spine of
a binder of FIG. 1.

FIG. 11 is an enlarged isometric inside view of the spine of
a binder of FIG. 1 taken along the indication circle of FIG.
2.

FIG. 12 is an enlarged isometric inside view of the spine of
a binder of FIG. 1 taken along the indication circle of FIG.
2; and,

FIG. 13 is an enlarged isometric inside view of the spine of
a binder of FIG. 1 taken along the indication circle of FIG.
2.

The broken lines showing of the binder represent the
environment of the claimed design. The broken lines form no
part of the claimed design. The dot-dash-dot lines shown in
the drawings form no part of the claimed design.

1 Claim, 8 Drawing Sheets
